His Attorney.

UNITED STATES PATENT OFFICE.

SIEGFRIED KOWALLIK, OF PANKOW, BERLIN, GERMANY, ASSIGNOR TO GENERAL ELECTRIC COMPANY, A CORPORATION OF NEW YORK.

ELECTRODE STEAM BOILER.

Application filed April 13, 1926, Serial No. 101,818, and in Germany April 30, 1925.

The present invention relates to electrode steam boilers, and more particularly to a means for removing from such boilers the salts and other impurities with which they 5 gradually become charged in operation, and which tend to cause undesirable overloading by increasing the conductivity of the boiler liquid.

The increased conductivity of the boiler 10 water is particularly noticeable in boilers not exclusively supplied with water of condensation. This includes the majority of electrode boilers, since it is the usual practice to feed such boilers with water from 15 various sources, along with condensate. The increased conductivity caused by impurities in the water supplied from the usual sources tends to overload the electrodes and the circuits connected therewith, unless the 20 impurities are drained off from time to time.

Apart from the special attendance required, this mode of operation has the disadvantage that the tendency is to operate the boiler with a water conductivity on the 25 average somewhat higher than that for which the boiler is designed. This in turn causes the regulation to become less sensitive, and causes the boiler to become over-loaded.

The object of the present invention is to 30 provide an improved arrangement in an electrode boiler whereby the boiler is automatically drained of deposits and other conductivity increasing impurities in such a manner that overloading beyond permissible 35 limits is prevented, and good regulation permitted for various loads, thus obviating the disadvantages above mentioned.

In carrying out the object of the invention, 40 an electrode boiler having a regulator responsive to a certain operating condition, such as the pressure delivered by the boiler for controlling its output, is provided with means in circuit with the electrodes which 45 is responsive to changes in current flow thereto, but which by connection with the regulator is rendered non-responsive to normal changes in current flow occasioned by 50 regulating operations of the boiler while the conductivity of the boiler water or liquid remains below a certain predetermined limit.

The current-responsive device is arranged 55 to control a drain valve, or other suitable drain means for the boiler, and operates to open said valve when the current flow to the

electrodes includes an added current value for any regulating position, over the normal value for that position, which added current value is set up by the presence of an undesirably large proportion of salts and other 60 conductivity increasing impurities in the boiler liquid.

For a further consideration of what is believed to be novel, and the invention, attention is now directed to the accompanying 65 drawing, the description taken in connection therewith, and the appended claims.

In the drawing, the figure is a diagrammatical illustration, partly in section, of an electrode boiler provided with an arrangement 70 embodying the invention.

Referring to the drawing, 5 is an electrode boiler having spaced, insulated electrodes 6, 7 and 8 suspended in a steam generating chamber 9, and arranged for three-phase 75 alternating-current operation, although any suitable number and arrangement of electrodes for either direct or alternating current operation may be provided. A perforated wall 10 separates the steam generating 80 chamber from a feed water supply basin 11 in the lower end of the boiler.

Condensate or feed water is supplied to the boiler through a conduit 12, in which is located a normally open, hand-control valve 85 13 and a valve 14. The latter valve is controlled by a float 15 located within the supply basin 11. The float and valve serve as an automatic means for maintaining a constant supply of liquid in the supply basin. The 90 float is shown in its normal position in which it holds the valve 14 closed. As the level of the liquid in the supply basin falls, the float follows and causes the valve 14 to open proportionately, thereby permitting the 95 liquid level to be restored to normal.

The liquid in the supply basin is delivered to the electrode chamber 9 through a conduit 16, in which is located a pump 17. The pump in the present example operates preferably at constant speed, and causes the liquid to pass from the supply basin to the electrode chamber. The liquid in the electrode chamber returns in part to the supply basin 100 through the perforated wall 10, and in part 105 is evaporated by the heat generated by the current flowing between the electrodes.

The rate of delivery by the pump may be regulated by any suitable means, and in the present example is regulated by a valve 18 110

located in the conduit 16. The increased opening of the valve, beyond a certain normal opening, causes the pump to deliver liquid to the electrode chamber in excess of that taken up by evaporation and by drainage through the perforated wall 10, thereby raising the liquid level in the electrode chamber. Similarly, a decreased opening of the valve 18 causes the pump to deliver a lesser amount of liquid to the electrode chamber 9 than is consumed by evaporation and by drainage to the supply basin, and a corresponding lowering of the liquid level in the electrode chamber 9.

As is well known, the regulation of an electrode boiler is readily effected by increasing or decreasing the depth of immersion of the electrodes, a greater production of steam accompanying a greater depth of immersion.

This method of regulation is carried out in the present example, with valve 18 serving as the regulating means for the boiler, although any other suitable method of regulating the boiler may be used. In the arrangement provided, the valve may be moved to cause the liquid level about the electrodes to raise or lower, thereby increasing or decreasing the resistance interposed between the electrodes, and the steam generating capacity of the boiler. A normally open valve 19 is also provided in the conduit 16. This valve may be partially closed, under certain operating conditions, to throttle the delivery of the pump and thus control the range of regulation of the valve 14. The boiler is provided with a steam delivery conduit 20 adjacent its top.

The boiler thus far described represents any suitable electrode boiler provided with means, such as valve 18, for regulating its output, the pump, regulating valve and the interior arrangement of the boiler as described and illustrated being adapted for controlling the depth of immersion of the fixed electrodes employed in the present example, that is, for permitting regulation of a boiler of the fixed electrode type.

The boiler is supplied with electric energy from a suitable source such as three-phase alternating-current supply-mains 21, electrodes 7 and 8 being directly connected therewith, and electrode 6 being connected therewith through a circuit wire 22, in which is located a current responsive device such as a solenoid magnet 23, provided with means for varying its operating setting for response to a certain current flow. In the present example, this means is represented by a tap-switch 24, arranged for varying the number of solenoid turns included in circuit. The tap-switch is connected by a sliding rod 25 with a piston 26 located in a cylinder 27, to which cylinder is supplied boiler pressure through a pressure conduit 28.

The boiler pressure is supplied above the piston 26 in opposition to the force exerted by a spring 29 located below the piston. Valve 18 is provided with an operating lever 30, which is connected with the rod 25 through a link 31, and is by this arrangement placed under control of the boiler pressure, along with tap-switch 24.

The piston and cylinder arrangement, together with valve 18, thus provides a pressure regulator for the boiler, and a control means for the tap-switch. The operation of the regulator is such that increased pressure in the boiler above a certain normal value causes the piston 26 to be moved downwardly, and the valve 18 to be correspondingly closed, thereby lowering the liquid level in the electrode chamber, and correspondingly lowering the output of the boiler, as hereinbefore described, while a decreased pressure in the boiler causes the piston to be moved upwardly by the spring to correspondingly open the valve 18, thereby raising the liquid level in the electrode chamber 9, and correspondingly increasing the output of the boiler. As the application of pressure regulators to such boilers is known and well understood, further description is believed to be unnecessary. The regulator piston is shown in its upper position in response to subnormal pressure in the boiler, under which condition the pump is supplying excess liquid to the electrode chamber to raise the liquid level and to increase the output of the boiler, thereby tending to restore the pressure to normal.

The solenoid coil is provided with a movable core 32 which carries an insulated bridging contact 33. The core is normally held in a partially withdrawn position with respect to the solenoid by a spring 34. The bridging contact, together with two fixed contacts 35, forms a switch, which, with the core in the position above mentioned, is in the open position. The switch is connected in circuit with a second solenoid coil 36 which is supplied with energy through the switch from suitable supply mains indicated at 37.

Solenoid 36 is provided with a movable core 38 which is operatively connected with a drain valve 39 in the bottom of the boiler through a lever 40 and a link 41. Valve 39 is of the self-closing type, and is opened by energizing solenoid 36 through closure of the switch provided by bridging contact 33 and fixed contacts 35.

This arrangement provides for automatically draining the boiler, in this case the supply basin 11, whenever the current flow to electrode 6 is in excess of the normal regulated value, that is, whenever salts and other impurities in the boiler increase beyond an undesirable proportion, as will be seen from the following description of the operation.

In the operation of the boiler, the pressure

increases and decreases slightly in response to decreases and increases in the demand for steam taken through the delivery conduit 20. The pressure regulator moves valve 18 in response to the pressure changes to increase or decrease the depth of immersion of the electrodes, thereby increasing or decreasing the current flow to electrode 6, and correspondingly increasing or decreasing the boiler output. Such changes in current flow are thus normal to the operation of the boiler, and within the limits of its capacity. They are not caused by the accumulation of impurities in the boiler, but, since the solenoid is in the working circuit, such changes cause a varying current flow therein. However, the tap-switch, by which the solenoid is controlled, is operated by the pressure regulator, as has been hereinbefore mentioned, and causes a greater number of solenoid turns to be included in the circuit as the pressure increases; that is, as the piston 26 moves downwardly in response to the increased pressure accompanying a decreased demand upon the boiler. Likewise, the regulator operates the tap-switch to place a lesser number of solenoid turns in circuit as the pressure decreases; that is, as the piston 26 moves upwardly in response to the decreased pressure accompanying an increased demand upon the boiler.

It will thus be seen that the tap-switch by its operation, in conjunction with the pressure regulator, provides a compensating control for the solenoid. It operates to cause the working current taken by electrode 6, which is substantially the same as that taken by the other electrodes, to flow through a varying number of turns in the solenoid, a greater number of turns being automatically provided when the current flow decreases, and a lesser number of turns being automatically provided when the current flow increases. In other words, the tap-switch 24 by its operation, in conjunction with the pressure regulator, prevents the solenoid 23 from operating in response to the normal changes in current flow as provided by the regulating operation of the boiler, and does this by automatically maintaining substantially a constant number of ampere turns in the solenoid for all conditions of operation of the boiler. The strength of spring 34 is so adjusted that the core 32 does not respond to the normal ampere turn value of the solenoid, thereby preventing the solenoid from effecting a closure of the switch until a certain predetermined increase in the current flow above the normal regulated value is brought about by the presence of salts and other conductivity increasing impurities in the boiler liquid.

Stated in another way, the solenoid and tap-switch provide an adjustable current-responsive means in connection with the

working or electrode circuit of the boiler, the operating setting of which means is represented by a certain working or electrode current flow and which setting, by connection with the regulator, is continually maintained above a point represented by the normal regulated value of the working current, by a certain predetermined amount.

By normal regulated value of the current is meant the value of the working or electrode current as established by the regulating means of the boiler when the boiler is substantially free of conductivity increasing impurities.

An increase in the conductivity of the liquid, because of an accumulation of salts or other impurities, therefore, causes an increase in the ampere turn value of the solenoid above normal for all conditions of regulation. In response to the increased ampere turns, the solenoid then causes the core 32 to move to close the circuit through contacts 35, thereby draining the boiler of the impurities through valve 39.

Solenoid 23, together with the drain valve which it controls, thus provides a means for draining the boiler of impurities in response to excessive working current to the electrode, while the tap-switch, in connection with the regulator, maintains the limit at which said means operates, continually above the normal working current by a certain amount as said current varies through its regulating range.

As soon as the conductivity of the liquid is returned to normal, solenoid 23 is no longer energized sufficiently to hold the bridging contact in the closed position, and valve 39 is then permitted to close through opening of the circuit through solenoid 36. The drain valve 39 is provided with an outlet conduit 42 which leads to any suitable drain, not shown.

The level of the liquid in the supply basin is automatically restored to normal during and following the drainage operation of the boiler by the lowering of the float 15 controlling inlet valve 14 according to the operation hereinbefore described.

To indicate approximately the condition of operation of the boiler, that is, the steam pressure, a pointer 43 connected with the rod 25 is arranged to move over a fixed scale 44. In the present example the pointer is provided in connection with the tap-switch 24.

From the foregoing description, it will be seen that the boiler is provided with an arrangement which operates automatically to drain the boiler whenever the conductivity of the liquid therein exceeds a certain predetermined value; that is, whenever the boiler tends to draw from the supply mains an excessive current caused by the presence of salts or other conductivity increasing im-

purities, and that the arrangement permits the boiler to operate in a normal manner throughout its full regulating range without interruption.

5 While the invention has been described and illustrated in connection with a simple electrode boiler provided with a pressure regulator and a simple tapped solenoid coil for operating the drain valve, it should be 10 understood that the invention is not limited thereto, but may be carried out by other means.

What I claim as new, and desire to secure by Letters Patent of the United States, is:

13 1. The combination with an electrode boiler of a drain means therefore which automatically operates in response to a certain predetermined abnormal current flow to a boiler electrode, and regulating means for 20 the boiler connected with said first-named means for preventing operation thereof while said current flow is within normal working limits.

2. The combination with an electrode boiler having means for regulating the flow of working current thereto, of means responsive to the flow of working current for draining the boiler, said current-responsive means being adjustable in its response to the value 30 of the working current, and means providing a connection between the regulating means and said current-responsive means whereby it is adjusted by said regulating means.

3. An electrode boiler having a regulator 35 which controls the working current, characterized by the fact that the boiler is provided with a deposit draining means which is controlled by the working current and operated by a certain excess over any regulated value of said working current.

4. The combination with an electrode boiler, of means for automatically draining said boiler, said means comprising a current-responsive device in circuit with an electrode, means responsive to the boiler pressure 45 connected with the current-responsive device to control the operation of the same, and a valve operated by said current-responsive device.

5. The combination with an electrode boiler, of a pressure regulator connected therewith, a solenoid coil, a tap-switch for said solenoid coil connected with said pres-

sure regulator, a switch operated by said solenoid coil, a drain valve for the boiler 55 controlled by said switch, and means forming a circuit through the solenoid coil and tap-switch to one of the boiler electrodes.

6. The combination with an electrode boiler having a regulator controlling the current flow to its electrodes, of an adjustable current-responsive device operated by the electrode current, a drain means for the boiler controlled by the current-responsive device, and means controlled by the regulator 65 for adjusting the current-responsive device for response to the electrode current above a certain predetermined value above the normal regulated value of the electrode current.

7. The combination with an electrode 70 boiler, of a regulator connected therewith for controlling the electrode current, in response to an operating condition of the boiler, a drain valve for the boiler, means responsive to the electrode current for opening said drain valve, said means being adjustable to respond to different values of electrode current, and means providing a connection between the regulator and said current-responsive means for adjusting the latter in accordance with the operation of the regulator for response to a current value above the normal regulated electrode current.

8. The combination with an electrode 75 boiler having a regulated electrode current, of means connected therewith for draining the boiler of impurities in response to a certain predetermined increase in the electrode current above the normal regulated value 80 thereof.

9. The combination with an electrode boiler having a working circuit, of an adjustable current-responsive device connected with said working circuit, said device having an operating setting represented by a certain 95 working current, means for draining the boiler connected with said device to be operated thereby, and means connected with the device for maintaining its operating setting above the normal regulated value of 100 the working current by a certain predetermined amount.

In witness whereof, I have hereunto set my hand this 23rd day of March, 1926.

SIEGFRIED KOWALLIK.
